UNITED STATES PATENT OFFICE

LOUIS MORRISON, OF NEW YORK, N. Y.

DESIGN FOR A CLIP FOR A FOUNTAIN PEN OR SIMILAR ARTICLE

Application filed April 26, 1930. Serial No. 35,402. Term of patent 7 years.

To all whom it may concern:

Be it known that I, LOUIS MORRISON, a citizen of the United States of America, residing at New York city, county and State of New York, have invented a new, original, and ornamental Design for a Clip for a Fountain Pen or Similar Article, of which the following is a specification, reference being had to the accompanying drawing forming part hereof, in which—

I claim:

The ornamental design for a clip for a fountain pen or similar article as shown.

Signed at New York city, this 24th day of April, 1930.

LOUIS MORRISON.
